CHARLES H. HODGKINS, OF PITTSBURGH, PENNSYLVANIA, ASSIGNOR TO WESTINGHOUSE ELECTRIC & MANUFACTURING COMPANY, A CORPORATION OF PENNSYLVANIA

THERMAL RELAY

Application filed September 29, 1931. Serial No. 565,744.

My invention relates to relays and particularly to thermally actuatable relays.

An object of my invention is to provide a relatively simple and highly efficient means in a thermal relay for varying the value of the current at which the relay will operate.

My invention is particularly applicable to an electromagnetic thermal relay embodying a current-traversed initially-magnetic member which becomes non-magnetic at a higher temperature, and, in practicing my invention, I provide an energizing coil and a strip or bar of a suitable magnetically-reversible metal, which strip or bar is normally operatively engaged by a portion of a pivotally-mounted armature structure, one portion of the armature structure being adjustable relatively to the strip or bar.

In the single sheet of drawing:

20 Figure 1 is a view partly in section and mainly in side elevation, of a thermal relay embodying my invention;

25 Fig. 2 is a top plan view of the device shown in Fig. 1, and

Fig. 3 is a view, in front elevation, of the device shown in Fig. 2 embodying my invention.

The assembly or structure of a relay 11 is so arranged as to be mounted on, and secured against, an insulating support 12 which may be either a suitable small panel of electric-insulating material, or it may be a switch-board panel of relatively large area. While I have shown such a structure, it is to be noted that my invention is not limited thereto but resides rather in certain elements to be hereinafter set forth in greater detail.

30 A magnetizable core 13 has its inner end engaging a magnetic member 14, the core member 13 being preferably of rod or circular bar shape, while the member 14 may be of substantially plate shape having one surface engaging the surface of base 12. A non-magnetic yoke portion 16, of substantially L-shape, has its shorter leg portion 17 secured to the front of the plate 14 by any suitable means such as by welding or in any other desired manner.

35 40 45 50 A series current-traversed coil 18 is shown schematically only in the drawing, and while

I have shown a coil constituted by a plurality of turns of a relatively heavy current conductor, I may use any other type of energizing coil or any suitable or desired current-traversed conductor. One terminal of the coil 18 is electrically connected to a bolt or stud 19 by means of which the relay 11 is secured to the base 12. The other terminal of coil 18 is connected to a connector 21 (see Fig. 3), which connector may be of substantially L-shape in section, the connection between the end of coil 18 and member 21 being made by a suitable bolt 22.

A second terminal stud 23 is located on the other side of the coil and core structure, and a second connector 24, also of L-shape, is provided, and a magnetically-reversible strip or bar 26 extends between the two connectors 21 and 24. This bar may be made of any one of several metals or alloys, and I prefer to use an alloy, usually called invar, which is a 35% or 36% nickel steel. This alloy has the characteristic of being susceptible to magnetism at relatively low temperatures, while it loses its magnetic properties or characteristics at temperatures on the order of 240° C. That is, while an element made of such nickel steel is magnetic at temperatures below approximately 240° C., it becomes non-magnetic at approximately this temperature and then becomes magnetic again upon reduction of temperature, thus having a thermally-variable magnetic characteristic. It is possible to vary the temperature value at which a bar or strip of this kind becomes non-magnetic by selection of the alloy, and the temperature mentioned is, therefore, given only for purposes of illustration.

The bar or strip 26 is secured to the two connectors 21 and 24 by any suitable means which may take the form of rivets 27. Further, the area of lateral section of the strip 26 is varied as may be noted by reference to Fig. 2 of the drawing, which shows that the lateral width of the strip 26 is less, adjacent to the connector 24, than it is at that end adjacent to connector 21. This will have the result that the temperature value at the reduced section, indicated generally by the numeral 28, will be higher than the tempera-

ture at full section 29, for any predetermined current value traversing the strip 26 after substantially constant temperature values have been established, as will be the case 5 after a certain length of time of operation at such predetermined current value.

An armature structure movable relatively to the non-magnetic support 16 and the core member 13 may comprise a magnetizable 10 member or bar 31 which may be of substantially L-shape in longitudinal section, one leg portion extending parallel to the support 16 and having a projecting knife edge 32 which is located in a shallow recess 33 adjacent to 15 the outer end of the bar 16. A magnetizable tongue member or portion 34 is adjustably and pivotally mounted on the aforesaid leg portion of armature 31 and may be secured 20 in proper or predetermined position relative- ly to member 31 by a spring nut 36 engaging a machine screw 37, which machine screw 37 extends through an elongated and laterally 25 extending slot 38 in the tongue member 34 (see Fig. 2). The inner end portion of the tongue member 34 may be offset, as is shown 30 in Fig. 1 of the drawing, and it may have a small rivet 39 projecting beyond that face which is adjacent to the invar strip 26. This 35 is for the purpose of concentrating the magnetizing flux which traverses the tongue member 34 and the initially magnetic invar strip 26.

Means for resiliently holding the armature structure, including the portions 31 and 34, 40 in substantially the positions shown in Fig. 1 of the drawing, include a stud 41 which is riveted to the non-magnetic member 16 adjacent the forward end thereof, which stud extends through suitable aligned openings in 45 the members 31 and 34, which openings are slightly larger than the stud itself to permit tilting motion of elements 31 and 34 relatively to the stud. A compression spring 42 surrounds the free end of the stud 41 and a washer 43 and a cotter pin 44 permit of giving the spring 42 an initial compression.

The forward end of member 34, which is in general of flat bar shape, may be pointed out as is shown at 46 in Fig. 3, and indicia may be 50 provided on the adjacent surface of member 31, as may be noted by reference to Fig. 3 of the drawing.

The hereinbefore-described construction permits of varying the position of the member 34, which it may be noted is also of magnetizable material such as iron or steel, relatively to the member 31, whereby the rivet 39 may be caused to normally operatively engage the upper surface of the invar bar 26 at predetermined points along its length. Thus, it is possible for the pointer 46 to be set so that it is above the word "Low" in Fig. 3, and the head of rivet 39 will have been moved toward the left on the invar strip 26 or to a portion of 60 65 the strip which will be at a higher tempera-

ture than other portions of the strip for a predetermined current traversing the coil and the strip 26. If it is desired to vary the adjustment, the spring nut 36 may be loosened and the member 34 turned relatively to the 70 member 31, using the stud 41 as a pivot point and the pointer 46 may thereby be moved over the word "High" in Fig. 3 of the drawing, when the head of the rivet 39 will operatively engage the invar strip 26 at a point 75 where its width is substantially normal.

While I have illustrated and described a structure in which one portion of the armature structure may have a turning or pivotal movement relatively to the other portion of 80 the armature structure, I do not desire to be limited thereto, as I may move the entire adjustable element laterally of the substantially fixed element, which latter element is member 31. 85

The relay operates by the downwardly depending armature 31 being attracted by the front end of the core 13, as soon as the invar strip loses a sufficient amount of its attraction for the rivet-end of the bar 34, the armature- 90 aggregate 31-34 pivoting at 32-33. It is obvious that, if the movable armature member 34 be so adjusted that the head of the rivet 39 engages the invar strip at its most restricted section 28, the relay will operate at 95 a predetermined value of current traversing the coil, which value is lower than would be required to effect operation of the relay if the movable armature member 34 were adjusted so that the head of the rivet 39 engaged the magnetically-reversible member at the large 100 section 29.

While I have shown no device which is to be actuated by the moving armature when the depending front leg portion of member 31 is drawn toward the end of core 13, which action occurs when the strip 26 or a predetermined portion thereof has reached the temperature at which that portion loses its magnetic characteristic, it is obvious that any mechanism may be actuated thereby, such as a push rod, which push rod may, in turn, open a circuit or actuate some other controlling mechanism, as shown, for example, in a patent to H. E. White, No. 1,675,680, July 3, 1928, assigned to the Westinghouse Electric & Manufacturing Company. In view of the well-known application of such elements, I have not thought it necessary or desirable to illustrate such details, as my invention relates more particularly to means for calibrating or adjusting one part of a thermal relay structure relatively to another part, whereby the value of current at which the relay will operate may be suitably varied. 110 115 120 125

Various modifications may be made in my invention without departing from the spirit and scope thereof, and I desire, therefore, that only such limitation shall be placed 130

thereon as are imposed by the prior art or are set forth in the appended claims.

I claim as my invention:

1. In a thermal relay including an energizing coil, a magnetic-circuit structure having an armature movable relatively to the coil, a heated fixed member having a thermally-variable magnetic characteristic and controlling the position of the armature, said armature having a portion adjustable relatively to the fixed member.
2. In a thermal relay including an energizing coil, a magnetic-circuit structure having an armature movable relatively to the coil, a fixed member heated in accordance with the current traversing the relay and having a thermally-variable magnetic characteristic controlling the position of the armature, said armature having a portion adjustable longitudinally relatively to the heated fixed member.
3. In a thermal relay having an energizing coil and a magnetic circuit structure including a plural part armature movable relatively to the coil, a heated member of varying area of cross-section and having a thermally-variable magnetic characteristic, means for holding said heated member in a fixed position, and means for locking one of said armature parts in predetermined selected position on the other part and longitudinally of the heated member to vary the operation of the relay.
4. In a thermal relay having a current-traversed member of varying area of cross-section and having a thermally-variable magnetic characteristic, means at its ends for supporting it in a fixed position, a magnetizing coil structure including a magnetizing coil and a plural-part armature movable relative to the coil, one part thereof being adjustable on the other longitudinally of the current-traversed member.
5. In a thermal relay having a magnetizing coil, a current-traversed bar of varying area of cross section between its ends, means for holding it in a fixed position relatively to the coil, a support, an armature structure pivotally mounted on the support and including two overlapping portions, and means operatively associated with said armature structure to normally hold the end of one of said overlapping portions in predetermined longitudinally-different positions against the current-traversed bar.
6. In a thermal relay including an energizing coil, a heated member having a thermally-variable magnetic characteristic, a magnetic-circuit structure including an armature embodying two relatively movable portions, means for pivotally mounting said armature, and means on the armature for locking one of the portions on the other to vary the position of the first portion longi-

tudinally of the heated member to vary the operating characteristic of the relay.

7. In a thermal relay including an energizing coil, a heated member having a thermally-variable magnetic characteristic and being of varying area of cross section between its ends, a current-traversed supporting means in series electric circuit with the energizing coil for holding the heated member in fixed position, a support, an armature pivotally mounted on the support and including two relatively movable portions, and means on the armature for locking one of the portions on the other to vary the position of one of the portions longitudinally of the heated member to vary the operating characteristic of the relay.

8. A thermal relay of the movable-armature type, comprising magnet-means for magnetizing said armature and for attracting said armature toward its moved position, and thermally responsive means for holding said armature in its initial position against the pull of said magnet-means, said thermally responsive means comprising a stationary, electric-current-traversed bar of a material which is magnetic when cold and which loses at least some of its magnetism when heated to a critical temperature, said bar being of such spatial disposition that different portions of its length reach said critical temperature at different values and/or times of flow of the current traversing the same, characterized by means for adjusting the end of the armature which normally contacts with said bar, so that said end of the armature may make its contact with the bar at different points along the length of the bar, whereby the current and/or time at which the bar releases the armature is varied.

9. The invention as specified in claim 8, characterized by said bar having a gradually diminishing cross-sectional area from one extreme of the adjustment of said armature to the other.

10. The invention as specified in claim 8 characterized by said armature being a composite member comprising two magnetizable plates pivoted together in face-to-face relation.

11. The invention as specified in claim 8, characterized by said bar having a gradually diminishing cross-sectional area from one extreme of the adjustment of said armature to the other, and further characterized by said armature being a composite member comprising two magnetizable plates pivoted together in face-to-face relation.

In testimony whereof, I have hereunto subscribed my name this 25th day of September, 1931.

CHARLES H. HODGKINS.
